United States Patent Office.

OBADIAH MARLAND, OF BOSTON, MASSACHUSETTS.

Letters Patent No. 91,142, dated June 8, 1869.

IMPROVEMENT IN HARDENING STEEL.

The Schedule referred to in these Letters Patent and making part of the same.

To all whom it may concern:

Be it known that I, OBADIAH MARLAND, of Boston, in the county of Suffolk, and State of Massachusetts, have invented Improvements in Hardening Steel; and I do hereby declare that the following, taken in connection with the drawings which accompany and form part of this specification, is a description of my invention, sufficient to enable those skilled in the art to practise it.

My invention has reference to a process and apparatus designed by me, primarily, for hardening sheets of considerable area and thickness, made up of layers of iron and steel combined, by welding, and designed for forming the walls of burglar-proof safes and vaults, or for employment as defensive armor-plates for war-vessels and fortifications, though my invention is applicable to hardening various objects of steel alone, or of steel and iron combined.

My invention may be said to consist in subjecting the hot metal to be hardened, to the action of a cold current, maintained under pressure, while it acts on the heated metal by means of a head or force, checked from free delivery or outlet, so that the current will press against the heated metal, and will flow past it rapidly, changing quickly the heated atoms of the current for cold atoms, and thus rapidly absorbing and carrying off the caloric from the heated metal. The current employed will generally and preferably be pure cold water, which may be supplied from a fall, head, or reservoir, or by a pump, but other liquids than water may be employed, or various fluid mixtures may be made use of, or substances soluble in water may be mixed therewith, or air, or gaseous, or vaporous currents may be used.

My invention further consists in the details of construction and arrangement, and the equivalents therefor, described beyond, with reference to the drawings, by which I practise my process of subjecting heated steel to the action of a retarded or checked current of cold fluid, under pressure.

Figure 1 shows a sectional elevation of my improved apparatus, and

Figure 2, a sectional plan of the same, arranged and designed for hardening sheets or plates of steel, or sheets or plates of welded layers of steel and iron.

a represents the sides, bottom, and top of a trough, designed to receive and hold vertically on its edge, the heated plate, *b*, the trough being given an inclination so that if the cooling-current is a liquid, it may drain freely from below the lower edge of the plate, which rests on a grid, or series of bars *c*, located above the inner surface of the bottom of the trough.

In recesses in the sides of the trough are fitted two adjustable vertical plates *d*, arranged so that they can be moved toward and from the trough-centre, said plates being provided on their adjacent faces with pins

or studs *e*, which come into contact with the sides of the hot metal plate, and keep the surfaces of the heated plate apart from the surfaces of the adjustable plates, so as to permit free flow of the cooling-current past the heated metal.

The pins or studs *e* are longer where the cooling-current enters and first strikes against the heated plate, than they are at the other end of said plate, this giving passage-ways which gradually contract and keep the atoms forming the cooling-current pressed against the sides of the heated plate, and increasing the velocity of the current as it progresses along the heated plate.

The top of the trough is provided with a cover or door, *g*, which, when opened allows the heated plate to be lowered into the trough till it rests on the bars *c*, and then either or both the side plates *d* are adjusted by means of the screws *f*, or other more quickly-moving mechanical devices, till the ends of the studs *e*, in both plates *d*, bear against the surfaces of the heated plate *b*.

The ends of the screws *f* are coupled to plates *d*, so as to retract said plates readily, as well as press them toward each other.

In place of the screws, toggle-joints may be used to press the plates *d* toward the heated plate, and to retract the plates *d*, and said toggle-joints may have their resisting pivots made movable, so as to adjust and adapt them to operate on any thickness of plate, said resisting pivots being made by screws adjustable as to position.

Then the cover *g* is closed over the plate *b*, leaving room, however, between the inner surface of the cover and the top edge of the plate, for the passage of the cooling-current.

At the outlet-end of the trough is provided any suitable check or valve, *h*, made adjustable, so as to contract the delivery from the trough, to any desired extent.

If the cooling-current is to be a liquid, supplied from a cistern, or reservoir, or head, then the inlet-end of the trough is provided with a valve or gate, *i*, which is to be turned or opened as soon as the plate *b* is fixed in place, and the cover *g* closed and secured. Then the liquid fills the trough instantly, and flowing past the plate *b* on all its surfaces, abstracts its heat very quickly, and hardens the plate, discharging the abstracted caloric with the current which escapes past the check *h*.

If the cooling-current is to be supplied by the action of a pump, fan, or bellows, then the valve or gate *i* may be dispensed with.

The plate *b*, when large, is manipulated in placing it in and removing it from the trough by the aid of cranes, and other suitable appliances.

To keep the lower edge of plate *b* from lodging

on the studs *e*, as it is lowered into the trough, suitable temporary fenders are made to extend down the plates *d*, between the studs *e*, said fenders being withdrawn previous to clamping the plate *b* between the studs.

When cooling-liquids are supplied from a head or reservoir, any leakage which takes place past the valve or gate *i*, will cause no trouble to the operatives in placing and securing the hot plate *b*, as the liquid will flow freely off under the supporting-bars *c*.

Near the check-valve in the trough are located bars *k*, against which the end of the heated plate abuts, which bars keep the plate from being moved along in the trough, toward the check-valve, by the force of the cooling-current.

The studs between which the heated plates are clamped being of equal lengths, where opposed to each other, said plates are subjected on each side to the action of equal quantities of the cooling-current, and the result is that the plates are hardened with very little warping or twisting.

I prefer in all cases to make use of the valve or gate *g*, as I do not believe that a pump or fan will act to deliver instantaneously a sufficient volume of cooling-current to produce the best possible results.

With a head of water of about ten pounds' pressure, and in sufficient quantity, I have hardened large, thick plates of combined welded layers of iron and steel, to an extent which rendered futile all attempts to drill the plates with the hardest steel drills.

The water used need not be wasted, and may be collected as it flows past the heated plate, and may be used again and again, by being pumped back into the elevated reservoir, which, if necessary, may be supplied with ice.

I claim—

1. The process for hardening steel, consisting in sub-

jecting the heated steel to the action of a cooling-current, which is maintained under pressure in a receptacle for the heated steel, through which receptacle the cooling-current flows, by the action of a head or pressure against a contracted outlet, substantially as described.

2. Also, a receptacle for the heated steel article, arranged with an inlet and outlet for the cooling-current, when shaped to correspond to the form of the piece to be hardened, and to permit a substantially uniform flow of the cooling-current past all the surfaces of said piece, substantially as described.

3. Also, a receptacle for the piece to be hardened, when provided with adjustable studs, arranged to clamp and hold said piece in position for the action thereon of the cooling-current.

4. Also, a receptacle for the piece to be hardened, when provided with an inlet-valve or gate, and a grid or series of bars, *c*, arranged to allow deposit or drainage of leakage of the cooling medium, and to admit the contact of the cooling-current with the lower surface of said piece.

5. Also, the combination of the check-bars *k* with the receptacle for the heated steel, substantially as and for the purpose specified.

6. Also, the combination, with the receptacle for the hot steel, of a cover or door, provided with means for locking it when closed, substantially as described.

7. Also, the combination, with the receptacle for the hot steel, of adjustable plates, arranged to contract the area of the passage of the cooling-current, as it passes from the inlet to the outlet, substantially as and for the purpose specified.

OBADIAH MARLAND.
